UNITED STATES PATENT OFFICE.

ADOLF KRUSE, OF HOBOKEN, NEW JERSEY.

DOOR-CHECK.

No. 806,545.

Specification of Letters Patent.

Patented Dec. 5, 1905.

Application filed July 21, 1905. Serial No. 270,726.

To all whom it may concern:

Be it known that I, ADOLF KRUSE, a citizen of the United States, residing in Hoboken, in the county of Hudson and State of New Jersey, have invented certain new and useful Improvements in Door-Checks, of which the following is a specification.

This invention relates to an improved safety door-check for doors which is intended to be used in place of the well-known safety-chains to prevent only the partial opening of the door and prevent forcible entrance.

One of the objects of the invention is to provide a device of this type which it is impossible to unlock or release except when the door is closed.

It is also an object of the invention to furnish a door-check which after having been released is automatically returned to operative position upon the closing of the door.

With these and other ends in view the invention consists in the novel features, arrangements, and combinations of parts to be hereinafter described, and recited in the claims.

In the accompanying drawings, in which corresponding parts are denoted by similar reference-letters, Figure 1 is a perspective view of one form of the improved door-check. Fig. 2 is a side elevation, partly in section, through the jamb of the door-frame; and Fig. 3 is a horizontal section on line 3 3, Fig. 1, showing the door and door-check in partially-open position.

Referring to the drawings, A indicates the jamb of a door-frame, and D the door hinged to said frame. Attached to the jamb A at a point below the lock of the door is an oblong plate a, which is slightly countersunk in one face of said jamb, as shown. Said plate a is provided at either side with a vertically-disposed lug a', made integral therewith, and between said lugs is pivoted, by means of a pin extending between the same, a hook-shaped check member of substantially U shape, the pivoted leg of said member being of greater length than the bent-up or outer leg of the same. The inner leg of said member is thus suspended from the lugs a' in such a manner as to lie closely against the door-jamb, and the distance between the upper portions of said legs is greater than at their lower portions for a purpose which will hereinafter appear. The upper extremity of the outer leg of said hook-shaped member is provided with an inclined head b'.

Attached near the outer edge of the door is

a latch-plate d, upon which is pivoted a lifting-latch f, which is guided in vertical direction by a keeper e, projecting outwardly at right angles from said plate, as shown, and 60 preferably made integral therewith. The keeper e is disposed below the pivotal connection of the hook-shaped check member b, so that in its position of rest the latch f, which rests upon the keeper e, is retained in horizontal alinement with the enlarged head b' in said check member. The latch f is provided at its free end with an offset portion f', extending at approximately right angles thereto. An extension-arm f'' is made integral 70 with said offset portion and extends parallel to the main portion of said latch in order to take into the open portion of the upwardly-disposed hook b. In order to guide the latch f into the keeper e, the latter is provided at 75 its upper portion with a curved surface e', over which said latch is designed to ride, as will be readily understood. The arm f'', which extends laterally from the offset f', extends to quite a distance beyond the member 80 b and is provided at its free ends with an enlargement f''' for permitting the easy lifting of the same.

When the door is locked, the parts are in the position shown in Fig. 1, the latch f being 85 retained by its keeper, while the extension or arm f'' takes into the hook b. As soon as the door is opened the lateral motion of the arm f'' is transmitted to the hook b, as said arm abuts against and presses inwardly the bent- 90 up leg of said hook, so that the latter is swung upwardly and into the room, as shown in Fig. 3, until the arm f'' after sliding along said hook abuts against the bent portion thereof, and thereby prevents the further opening of 95 the door. When it is desired to open the door, it has to be returned to closed position, after which the latch and extension-arm are lifted by taking hold of the enlargement f''' so that said latch clears the keeper e and said 100 extension-arm clears the head b'. The door can then be opened, the check member b remaining immovable. When the door is closed again, the extension-arm f'' rides over the inclined head b' and takes into the member b, 105 while the latch proper rides over the curved portion e' of the keeper and drops into the latter, the parts being thus restored to their normal or operative position.

When it is not desired to use the safety-check, the latch is moved on its pivot to an angle of two hundred and seventy degrees, so

that it is suspended in the position shown in dotted lines in Fig. 1. The door can then be completely opened, all the parts of the safety-check being rendered inoperative. When the 5 door-check is in its normal or operative position, a person leaving the house lifts the latch so as to clear the inclined head and the latch-keeper, then opens the door, and closes it when outside. The extension-arm meanwhile 10 passes over the inclined head of the hook-shaped member and drops into said member, while the latch is again in a position to be vertically guided by its keeper. The door-check is thereby returned into normal position 15 automatically upon the closing of the door and does not have to be adjusted, as is the case with the safety-chains now in use.

Having thus described my invention, I claim as new and desire to secure by Letters Patent—

- 20 1. The combination, with a door and door-jamb, of a check member suspended from the latter, and a lifting-latch on the door movable into and out of said member.
- 25 2. The combination, with a door and door-jamb, of a check member suspended from the latter, and a member on the door movable into and out of coöperative relation with said check member only when the latter is in pendent position.
- 30 3. In a check device for doors, a vertically-swinging hook-shaped member attached to the door-jamb, and a device on the door movable into and out of said member only when the latter is disposed vertically.
- 35 4. The combination with the door and door-jamb, of a check member pivoted to the latter, and a lifting-latch on the door movable into and out of coöperative relation with said check member only when the latter is in pendent position.

5. In combination, a latch pivoted to the door, and a hook-shaped member on the door-jamb into and out of which said latch is movable, said latch being automatically returned into said member, after release therefrom, 45 upon the closing of the door.

6. The combination, with a door and door-jamb, of a hook-shaped check member suspended from the latter and provided with an inclined head, and a latch pivoted to the door 50 and designed to ride over said head and take into said check member, being slidable therein.

7. In a check device for doors, in combination, a hook-shaped member pivoted to the door-jamb to swing vertically, and a member 55 on the door movable into and out of said first-named member, said door member automatically taking into said hook-shaped member when the door is closed.

8. In a check device for doors, the combination, with the door and door-jamb, of a check member suspended from the latter, and a device on the door movable into coöperative relation with said member only when the latter is in pendent position, and automatically returnable into such relation, after release therefrom, 60 when the door is closed.

9. The combination, with a hook-shaped member pivoted to the door-jamb and provided at the upper end of its outer leg with 70 an inclined head, of a latch pivoted to the door and provided with an extension-arm normally in horizontal alinement with said head.

In testimony that I claim the foregoing as my invention I have signed my name in presence of two subscribing witnesses.

ADOLF KRUSE.
